2025 RELEASE UNDER E.O. 14176

UNITED STATES PATENT OFFICE.

ALBERT WM. GABEL, OF ROCHESTER, NEW YORK.

LICENSE-BRACKET.

1,387,846.

Specification of Letters Patent. Patented Aug. 16, 1921.

Application filed November 8, 1919. Serial No. 336,577.

To all whom it may concern:

Be it known that I, ALBERT W. GABEL, a citizen of the United States, residing at Rochester, in the county of Monroe and State of New York, have invented certain new and useful Improvements in License-Brackets, of which the following is a specification.

This invention has relation to brackets and more particularly to a support for brackets adapted to have secured thereto a license plate, such as are required for automobiles, trucks or other motor vehicles.

The primary object of the invention is to provide a bracket which may be patterned or cut from a blank with a minimum amount of waste material and which comprises but few and simple parts.

A further object of the invention is to provide a bracket of the character above described which can be readily and easily attached to any type of motor vehicle without the requiring of any special clamping means and which is further adapted for the reception of means for illuminating the number plate carried by the bracket.

The invention further consists in the details of construction and combination of parts as are hereinafter more particularly pointed out in the specification and illustrated in the drawings, in which—

Figure 1 is a front view of the completed bracket.

Fig. 2 is a vertical section taken on the line 2—2 of Fig. 1.

Fig. 3 is a plan view of the lens plate of the bracket, cut to shape and preparatory to being bent as indicated by the dotted lines.

Fig. 4 is a similar view of the body or main plate of the bracket and

Fig. 5 is a top view of the bracket with a lens plate and body portion assembled.

The blank from which this improved bracket may be stamped may be either of square or substantially rectangular shape, it depending upon the size to which the bracket is to be made. Both pieces of the bracket are preferably stamped from the same blank so as to provide for a saving in material and it may be so patterned as to be stamped from the blank with only a minimum waste. The numeral 1 indicates the main or body plate of the bracket which is to be cut to the shape represented in Fig. 4 having the edges 2 and 3 parallel to each other and perpendicular with respect to the

bottom edge 4. The plate is cut away along its other edge from a point 5 centrally located with respect to the opposite edges 2 and 3, to provide inwardly sloping edges 6 and 7 respectively. Each of the sloping edges 6 and 7 terminates abruptly from the vertical plane of the parallel edges 2 and 3 and are joined to the latter by means of the edges 8. The bracket is further provided with a number of suitable slots 9 through which any suitable form of fastening device may be inserted for attaching the bracket to an automobile, the particular form of fastening element suggesting itself in accordance with the construction of the vehicle frame to which the bracket is to be attached.

The lens plate 10 as will be noted, is of a substantially triangular shape and is provided with blunt extremities 11. An opening 12 is disposed centrally through the lens plate and is adapted to be covered by a lens 13, supported by an annular flange 14. This flange 14 may be a separate piece soldered about the opening 12, or may be provided by a number of radial slits about the edge of the opening 12, portions of the edges between certain slits being bent to extend outwardly and against the lens member 13.

The dotted line structure illustrated in Figs. 3 and 4 indicates the lines upon which the various portions of the members 1 and 10 are bent, prior to their being joined together. The edge portions 2, 3 and 4 of the body member 1 are bent upwardly along their respective dotted lines to extend in substantially vertical relation to the body portion 1 and in a similar manner the marginal portion lying between the dotted lines 15 and the edges 6, 7 and 8 are likewise bent upwardly so as to be substantially perpendicular to the plane of the body member, in which position it is to be observed that the sloping edges 6 and 7 are substantially parallel with the body member 1, while the edges 8 are at an angle therewith. The marginal portion of the lens plate 10 may be bent upwardly in the same manner as were the portions of the bracket 1 with the exception that the triangular ends 16 of the lens plate are bent so as to extend angularly from the lens plate and with this distinction: namely, that as the marginal portions of the bracket body are vertically disposed forward of what may be termed the front face of the bracket plate, in the case of the lens plate, the marginal portion

and triangular ends extend rearwardly of what is the front face of the lens plate when it is attached to the bracket member 1.

In joining the members 1 and 10 after 5 having been properly cut out and stamped to the required shape and size, the lens plate is placed upon the member 1 so that the apex 6 coincides with the apex 5 of the member 1 while the sloping flanges 17 fit 10 over the edges 6 and 7 respectively, thus permitting the triangular end 16 to fit snugly against the edges 8; these edges being overflanged by the bent portions of the end 16. Any improved method of sealing 15 the joints between the engaging edges of the two members may then be employed for uniting the two elements in a unified structure. The bracket is thus completed and forms a suitable support or carrier for any 20 license plate, such as indicated by numeral 18 in the drawings, which should be fastened to the bracket by any suitable means 19. The license plate should be further slotted as at 20; the slots of the license plate 25 being adapted to register with the slots of the bracket to permit passage of the fastening means therethrough for securing the bracket to the automobile frame. The upper portion 21 as well as the bent over 30 sloping portion should be finished off and polished so as to provide a reflector for the

lamp so as to direct light down upon the number plate so that the latter may be illuminated at night.

While the above constitutes the preferred embodiment of the invention, it is to be understood that such minor changes as are desired may be made as fall within the scope of the invention claimed.

Having thus fully described the invention, what is claimed as new is:—

A device of the character specified comprising a flat plate slotted at predetermined points to define a space for locating a license plate thereon and having side edges 40 beyond the space beveling to a point on one side of the plate, one beveled side having upstanding flanges angularly inclined with respect to each other to provide reflectors 45 for reflecting light upon the license space 50 and illuminating means between the said reflector and a cap-plate bridging the space between the flanges and supported by the latter for incasing the illuminated means, said cap-plate having lens-opening in line 55 with the illuminating means.

In testimony whereof I affix my signature in presence of two witnesses.

ALBERT WM. GABEL.
